UNITED STATES PATENT OFFICE.

THOMAS J. HOWSON, OF MARSHFIELD, OREGON.

WIRE PULLER AND TWISTER FOR CONCRETE FRAMEWORK.

Application filed June 30, 1927, Serial No. 202,586.

This invention relates to new and useful improvements in wire working tools and aims to provide a highly novel simple, and efficient wire puller and twister for concrete 5 formwork.

In the construction of concrete buildings it is necessary that a number of forms be constructed the purpose of which is to retain the walls during the process of hardening.

10 When the forms are put in it is necessary that they should be wired together, otherwise they would spread while the concrete is being settled and tamped.

In placing the wires through the form it is 15 the usual process to put a gimlet hole through the forms and extend from the board on one side to the board on the other side crossing over, say to the right, four or five inches and back again to the same board.

20 The method of fastening the boards so as to hold them in place has heretofore been to take the two ends of the wire and twist them either by hand or with a piece of steel or other metal to the proper tension. It is also 25 the custom to take a nail or a piece of steel or some suitable metal inside the form and give the wires a twist or two at that point. Naturally this is a slow and tedious process.

By reason of my improved device the ends 30 of the wire may be securely locked to the tool after which the ends of the wire may be twisted together. After this twisting operation a swivel hook-shaped fulcrum associated with the inner end of the tool is placed 35 against the wall of the form after which the tool is forced downwardly. The purpose is to tighten or draw the forms closer together. This action dispenses with the necessity of twisting the wires in the middle of the form which will prevent the wires from 40 being removed for further usage after the concrete has settled. Furthermore it will by reason of this tool not be necessary to enter the form as the entire job may be completed from the outside. Furthermore, the 45 drawing and twisting of the wire may be done in a rapid manner and without requiring much effort on the part of the workman. In the drawing, wherein like numerals indicate like parts throughout the several views:

Figure 1 is a side elevation of my improved tool,

Figure 2 is a detail longitudinal section thereof, and,

55 Figure 3 is a transverse section taken substantially upon the line 3—3 of Figure 2.

Now having particular reference to the drawings my improved tool consists of a tubular bar 5 of predetermined length and diameter the forward end of the bar being 60 outwardly flanged as at 6. Loosely arranged upon the tube directly in back of this flange is a ring 7 formed with a forwardly and downwardly extending hook 8 the point of which is sharpened so that it 65 may be forced into one of the boards of a wooden concrete form, to function as a fulcrum for the bar 5. Directly in back of this ring 7 said bar is formed externally with a collar 9 that is in turn formed with 70 radiating and spaced parallel ears 10—10 between which the tubular bar 5 is longitudinally slotted as at 11. Pivoted between these ears as at 12 is a lever 13 the inner end of which extends into the bar 5 through the slot 11 and that is formed at the inner extremity with a curved foot 14 provided with teeth 15 so that when said lever 13 is rocked downwardly this foot will bind the 75 ends of the concrete form wire A firmly 80 against the bottom interior surface of said bar for preventing the same from slipping therefrom.

The lever 13 extends upwardly and rearwardly from the ears 10 and thence directly 85 rearwardly the extreme end thereof being equipped with a suitable handle 16.

Obviously, when the lever is swung in an upward direction for releasing the clamping foot 14 from the inner surface of the 90 bar 5 the ends of the concrete form wire may be arranged within the forward end of the bar. By moving downwardly upon the handle the clamping foot 14 will firmly bind the ends of the wire within the tubular bar whereupon the ends of the wire may be 95 intertwined by turning the tool. After the proper twisting has been brought about the hook-shaped fulcrum 8 is engaged against the form and the tool thence rocked downwardly for further tightly drawing the wire upon the form. When it is desired to remove the wire the twisted ends are snipped after which one end of the wire is arranged 100 within the tool and firmly clamped therein 105 after which the wire may be easily torn from the form by a pull upon the tool.

It will thus be seen that I have provided a highly novel, simple and efficient wire pulling and twisting devise for concrete form 110 work that is well adapted for the purpose heretofore designated and even though I

have herein shown and described the invention as consisting of certain detailed structural elements, it is nevertheless to be understood that some changes may be made 5 therein without affecting the scope of the appended claims.

Having thus described my invention, what I claim as new is:—

1. In a wire pulling and twisting device of 10 the character described, a hollow bar member, a forwardly projecting foot swivelly arranged upon the inner end of the bar to provide a fulcrum for the bar, a handle lever pivoted adjacent the forward end of 15 the bar and a clamping foot associated with the lever and extending into the bar for clamping the ends of the wire within said bar.
2. In a wire pulling and twisting implement of the character described, a relatively 20 elongated bar member within which the ends

of the wire to be pulled and twisted are to be arranged, a lever pivoted adjacent the forward end of the bar the outer end of said lever extending rearwardly with respect 25 to the bar and a clamping foot arranged upon the inner end of the lever, said foot being arranged within the forward end of the bar and adapted to clamp the wire within the bar when the said hand lever is 30 depressed.

3. In a wire pulling and twisting device of the class described, a relatively elongated hollow bar member within the forward end of which the ends of the wire to be stretched 35 are disposed, a swivelled fulcrum associated with the forward end of the bar and means associated with the bar engageable within the bar for clamping the ends of the wire within said bar. 40

In testimony whereof I affix my signature.
THOMAS J. HOWSON.
